[57] CLAIM

The ornamental design for a combined cosmetic applicator and cap, as shown and described.

DESCRIPTION

FIG. 1 is a perspective view of a combined cosmetic applicator and cap showing my new design;

FIG. 2 is a front elevational view thereof, the rear view appearing the same;

FIG. 3 is a right side elevational view thereof, the left side view appearing the same;

FIG. 4 is a top plan view thereof;

FIG. 5 is a bottom plan view thereof;

FIG. 6 is a perspective view thereof with the cap removed for clarity of illustration;

FIG. 7 is a front elevational view thereof, the rear view appearing the same;

FIG. 8 is a right side elevational view thereof, the left side view appearing the same;

FIG. 9 is a top plan view thereof;

FIG. 10 is a bottom plan view thereof;

FIG. 11 is a front elevational view of the cap portion of FIG. 1;

FIG. 12 is a right side elevational view thereof, the left side view appearing the same;

FIG. 13 is a top plan view thereof; and

FIG. 14 is a bottom plan view thereof.
